UNITED STATES PATENT OFFICE.

WILLIAM H. PEPPER AND ALBERT T. L. DAVIS, OF LACONIA, NEW HAMPSHIRE.

DESIGN FOR A PATTERN FOR KNIT FABRICS.

SPECIFICATION forming part of Design No. 25,016, dated December 24, 1895.

Application filed November 9, 1895. Serial No. 568,496. Term of patent 7 years.

To all whom it may concern:

Be it known that we, WILLIAM H. PEPPER and ALBERT T. L. DAVIS, of Laconia, in the county of Belknap and State of New Hampshire, have invented and produced a new and original Design for a Pattern for Knit Fabrics, of which the following is a specification.

Our new and original design of a pattern for knit fabrics is illustrated in the accompanying drawing, which shows a plan view of a knit fabric with the designed pattern applied thereto.

As shown in the drawing, the pattern is composed of squares, blocks, or rectangles A B, of contrasting colors, the squares being arranged alternately both longitudinally and transversely, so that a "checker-board" effect is produced. Each square or block is composed of parallel alternating wales or stripes *a* *b*, of contrasting colors, the wales or stripes *a* being the predominating and characteristic ones

in squares A, whereas the wales or stripes *b* are the predominating and characteristic ones in the squares B.

The essential feature of the design consists 25 of the alternating rectangles, each composed of parallel stripes so disposed that certain of the stripes predominate in one-half the rectangles, while other of the stripes predominate in the other rectangles. 30

We claim as our design—

The design for a pattern for knit fabrics, as shown and described.

In witness whereof we have hereunto signed our names in the presence of two subscribing 35 witnesses.

WILLIAM H. PEPPER.
ALBERT T. L. DAVIS.
